DISPENSER FOR HEATING CREAMS, FOAMS, LOTIONS AND THE LIKE

George L. Schick, Trumbull, Conn., assignor to Warner-Lambert Company, Morris Plains, N.J.

Filed May 6, 1974, Ser. No. 467,329

Term of patent 14 years

Int. Cl. D9—01

U.S. Cl. D6—95

Fig. 1

Fig. 2

Fig. 3

Fig. 4

FIG. 5

FIG. 6

FIG. 7

FIG. 1 is a perspective view of a dispenser for heating creams, foams, lotions and the like showing my new design;

FIG. 2 is a front elevational view thereof;

FIG. 3 is a top plan view thereof;

FIG. 4 is a bottom plan view thereof;

FIG. 5 is a side elevational view thereof; and

FIG. 6 is another side elevational view thereof; and

FIG. 7 is a rear elevational view thereof.

I claim:

The ornamental design for a dispenser for heating creams, foams, lotions and the like, as shown.
